UNITED STATES PATENT OFFICE

WILLIAM W. WINGO, SAMUEL R. SMEDLEY, AND POLK C. BABE, OF POTEAU, OKLAHOMA

SAFETY GAS LIGHTER

Application filed October 8, 1931. Serial No. 587,718.

This invention relates to a safety gas lighter designed primarily for use in connection with gas cooking stoves, but it is to be understood that a gas lighter in accordance 5 with this invention is adapted for use in any connection for which it may be found applicable, by way of example with gas heaters, furnaces and boilers, and the invention has for its object to provide, in a manner as hereinafter set forth, a device for lighting gas burners to overcome the employment of matches and torches for such purpose, and to insure to the operator a maximum degree 10 of safety when operating the device to light a burner or burners.

Further objects of the invention are to provide, in a manner as hereinafter set forth, a device of the class referred to which is simple in its construction and arrangement, 20 strong, durable, compact, thoroughly efficient in its use, conveniently operated, readily installed in required position with respect to gas burner or burners, and comparatively inexpensive to manufacture.

To the above ends essentially the invention consists of such parts and in such combination of parts as fall within the scope of the invention as claimed.

In the drawing:

Figure 1 is a front elevation of a safety gas lighting device in accordance with this invention, and illustrating, by way of example, the adaptation of the device with respect to the top and burners of a gas cooking stove. 30 The stove top being shown in longitudinal section and the burners in edge elevation.

Figure 2 is a section on line 2-2 Figure 1.

Figure 3 is a section on line 3-3 Figure 1.

Figure 4 is a section on line 4-4 Figure 1. 40 Figure 5 is an end view of the device showing the bearing for one end of the operating shaft.

The device includes a support referred to generally at 1 and of angle shaped cross section. The support 1 comprises an elongated vertical part or flange 2 and an elongated horizontal part or flange 3 which is disposed at right angles to 45 and is integral with the upper end of part 2. Formed integrally with one end of the parts 2, 3 is a vertical, square

end part 4 having a central opening 5. The part 4 corresponds in height to that of part 2. Adjacent the other end of parts 2, 3 and integral with part 2 is a bearing member 6 which is arranged below and is parallel to 55 part 3. The part 2 is of uniform height throughout. The part 3 is formed of two portions of different width, the wider indicated at 7 and the narrower at 8. The width of portion 7 corresponds to the height of part 2 and to the width of part 4. The length of portion 8 is greater than that of portion 7. 60

The part 2 is formed with a plurality of spaced sets of spaced openings disposed lengthwise thereof. The openings of one set being indicated at 9 and the openings of the other set at 10. The portion 7 of the part 3 is formed with an opening 11.

The support 1 is pivotally suspended from the top 13 of the stove by a hanger device 70 and the latter includes a pivot bolt 14, a sleeve 15 and a square nut 16. The bolt 14 extends upwardly through the opening 11, sleeve 15 and an opening 17 formed in the stove top 13. A binding screw 17' is provided for bolt 14. 75 One part of the wall of opening 17 is circular and the other part square. The width of the squared portion of opening 17 is greater than the diameter of the circular portion of such opening thereby providing a shoulder 18. The nut 16 is mounted upon the upper end 80 of the bolt 14 and is mounted against shoulder 18. The sleeve 15 extends into the circular portion of opening 17 and is interposed between nut 16 and part 3.

The device will be set up in a manner whereby it can be positioned relative to the gas burners to light the latter. As shown the device, by way of example includes two 85 sparker mechanisms, each consisting of a corrugated wheel 20 of any suitable material capable of cooperating with a flint to create a spark, preferably, the material will be carbonium, a tubular holder 21 disposed at right angles to the edge of wheel 20, a flint 22 within holder 21 and bearing against the edge of wheel 20, a pushing spring 23 within holder 21 bearing against flint 22, and an adjustable tensioning cap member 24 for spring 23. The wheel 20 is mounted in a yoke 25 90

which is integral with one end of holder 21. The holder is peripherally threaded and carries a clamp nut 26. The holder 21 of a sparker mechanism is adapted to extend through a selected opening of one of the sets 5 of openings. The nut 26 in connection with the base of the yoke 25 clamps the sparker mechanisms to part 3. The cap member 24 is interiorly threaded. The openings 9 and 10 permit for adjustably positioning the 10 holders relative to part 3.

The wheels 20 and holders 21 are arranged below the reduced portion of part 3. The wheels 20 when the device is shifted in position will be in proximity to the burners 19 in a manner as shown in Figure 2. The part 15 3 is reduced so as not to interfere with the jumping of the sparks in a direction to ignite the gas when the burners are turned on.

The device includes an operating shaft 27 of polygonal cross section, preferably triangular as shown. The wheels 20 have axial openings 28 corresponding in contour to that of the cross sectional shape of shaft 27. The 20 wheels 20 have a snug fit with shaft 27 and are rotated thereby. A wheel 20 and the flint holder may be adjusted as a unit with respect to bar 1 to any one of the openings of either set of openings. The shaft 27 extends 25 through the opening 5 in the part 4, through the bearing member 6 and through openings 29 formed in the arms of yoke 25. The shaft has a reduced peripherally threaded inner end 29 which carries a retaining nut 30 to 30 prevent the pulling of the shaft outwardly. The outer end of shaft 27 carries a thumb piece or grip 31 to facilitate the rotation thereof, and on its rotation it will cause the wheels 20 to coact with the flints 22 to create 35 sparks for lighting the gas when a burner or burners is or are turned on.

What we claim is:—

1. A safety lighter for gas burners comprising a support including a vertical and 45 a horizontal part disposed at right angles to each other, hanger means engaging with said horizontal part for suspending the support, an operating shaft connected to the support, and sparker mechanisms operated from said 50 shaft, one of the elements of each of said mechanisms being supported and rotated by said shaft, and the other of the elements of each of said mechanisms being supported from said vertical part and opposing said 55 rotatable elements.

2. A safety lighter for gas burners comprising a support formed of a pair of flanges disposed at right angles to each other, a plurality of spaced sparker mechanism, an operating shaft common to the latter and rotatably carried by said support, each of said mechanisms having a rotatable element carried and bodily moving with said shaft, each 60 of said mechanisms having the remaining elements thereof supported from one of the 65

flanges in a direction at right angles to the axis of said shaft, and the said remaining elements including a spring pressed flint, said flints permanently bearing against the edges of said rotatable elements. 70

3. A safety lighter for gas burners comprising a support formed of a pair of flanges disposed at right angles to each other, a plurality of spaced sparker mechanisms, an operating shaft common to the latter and rotatably carried by said support, each of said mechanisms having a rotatable element carried and bodily moving with said shaft, each of said mechanisms having the remaining elements thereof supported from one of the 75 flanges in a direction at right angles to the axis of said shaft, and the said remaining elements including a spring pressed flint, said flints permanently bearing against the edges of said rotatable elements, the other of said flanges including a wide and a narrow part, said narrow part arranged over said mechanisms. 80

4. A safety lighter for gas burners comprising a support formed of a pair of flanges 90 disposed at right angles to each other, a plurality of spaced sparker mechanisms, an operating shaft common to the latter and rotatably carried by said support, each of said mechanisms having a rotatable element carried and bodily moving with said shaft, each of said mechanisms having the remaining elements thereof supported from one of the flanges in a direction at right angles to the axis of said shaft, the said remaining elements including a spring pressed flint, said flints permanently bearing against the edges of said rotatable elements, suspension means 95 for said support connected to the other of said flanges, and the said other of said flanges including a wide and a narrow part, said narrow part arranged over said mechanisms. 100

In testimony whereof, we affix our signatures hereto.

WILLIAM W. WINGO.
